UNITED STATES PATENT OFFICE.

JAMES L. MYERS AND WALTER J. SIX, OF CLEVELAND, OHIO.

LOCK FOR AUTOMOBILES.

Application filed October 19, 1921. Serial No. 508,790.

To all whom it may concern:

Be it known that we, JAMES L. MYERS and WALTER J. Six, citizens of the United States, and residents of Cleveland, county 5 of Cuyahoga, State of Ohio, have jointly invented a new and useful Improvement in Locks for Automobiles, of which the following is a specification, the principle of the invention being herein explained and the 10 best mode in which we have contemplated applying that principle, so as to distinguish it from other inventions.

The present invention, relating as indicated, to locks for internal combustion engines, 15 is particularly directed to an improved mechanism adapted to be attached to an internal combustion engine in use either in motor driven vehicles, or elsewhere, for the purpose of enclosing the spark plugs of the 20 engine and short circuiting the same when the engine is not in use. The present device is intended to completely enclose the spark plugs of the motor and to prevent access thereto as well as short circuit the plugs. 25 To the accomplishment of the foregoing and related ends, said invention, then, consists of the means hereinafter fully described and particularly pointed out in the claims.

The annexed drawing and the following 30 description set forth in detail certain mechanism embodying the invention, such disclosed means constituting, however, but one of various mechanical forms in which the principle of the invention may be used.

35 In said annexed drawing:—

Fig. 1 is a side elevation of an engine to which our improved device has been applied; Fig. 2 is a longitudinally horizontal section through the enclosed casing thereof; 40 Fig. 3 is a vertical section on line 3—3 of Fig. 2; Fig. 4 is a transverse vertical section on the line 4—4 of Fig. 2; and Fig. 5 is a plan view of a modified type of locking bar.

45 In Fig. 1, I have shown a motor 1 which is provided with two cylinder blocks 2 and 2' in each of which there are two cylinders, each of which is provided with a spark plug 3. It will be understood of course that the 50 present invention is in no way limited to a four-cylinder engine and may be equally well adapted for use on engines with various numbers of cylinders.

55 Our improved device consists of a sheet metal box-like casing 4, open at its top, which is adapted to be set over the spark

plugs on the top or side of the motor. This casing is provided with a series of depressed bosses 6, each of which is provided with an aperture 7 constructed to fit snugly over a 60 spark plug 3 of the engine. The spark plugs are usually set into a recess formed in a cylinder wall, and the boss 6 is designed to fit into this recess so that the base 8 of the casing, may rest flatly against the wall of the 65 motor. The casing is then fastened to the cylinder walls by means of the cylinder head bolts 9 and spark plugs which pass through suitable openings in the casing. In the event that the motor is provided with an integral head, bolts may be secured to the motor for passing through the apertures in the casing and permitting the latter to be bolted 70 securely to the engine.

The casing 4 is provided with an extending portion 10 at one end in which there is mounted a lock mechanism 11 which may be of any suitable construction and which is designed to permit the operation in the casing of a rod or bar 12. This bar is normally 80 held in the retracted position which is shown in Fig. 2, by means of a tension spring 13, which is fastened to the bar and to one of the walls of the casing.

The casing is provided with a removable 85 cap or cover 14 which has a flange extending downward from its edges, this flange fitting snugly over and against the upper edges of the side walls of the casing. In one end the cover is provided with two lugs 15 on 90 the flange, which are adapted to fit snugly into recesses 16 formed in the end wall of the casing 4. The engagement of these lugs in the openings, prevents the removal of the cover by lifting this end of it, and the other 95 end is secured by means of the bar 12 in the following manner. On the inside of this other end of the cover is a depending lug 17 adapted to fit between upwardly projecting lugs 18 and 19 on the inside of the casing. 100 The lugs 17, 18 and 19 are provided with openings which register when the cover is in position on the casing, and permit the bar 12, to be moved longitudinally into engagement with the openings in the lugs 17 and 19. The bar is at all times held in the opening in the lug 18 which acts as a guide for the forward end of this rod. When the bar has been removed to lock together the lugs 17, 18 and 19, the cover is securely fastened 105 to the casing and cannot be removed by any means short of destruction of the entire cas-

ing, and any means of destruction of the casing will also break or destroy the spark plugs, and hence render the engine inoperable.

- 5   Mounted on the bar 12 at intervals which are the same as the distance between the spark plugs 3, are coiled springs 25. When the bar 12 is moved to the right these springs are brought into contact with the 10 spark plugs 3, and ground the same, so that no spark can be obtained at the points of the plugs so long as the bar is in this position. In this way the engine is effectually locked against operation.
- 15   In Fig. 5 there is shown a bar 40 which is provided with springs 42 mounted thereon, but insulated from the bar. These 20 springs correspond with the springs 25 which are shown in Fig. 2, but in this case the wires 44, leading to the spark plugs which enter the box through openings 46, are connected to the springs and the circuit is then closed through these wires and the 25 spring to the spark plug. If the bar is moved to the left and the springs thereby moved out of contact with the spark plugs the circuit is broken instead of being merely grounded, as is the case with the construction already described.
- 30   Any suitable lock mechanism may be mounted in the hollow barrel-like end 10 of the casing, which is adapted to be mounted either in the dash or instrument board of the automobile, or allowed to remain under 35 the hood, depending upon whichever arrangement may be most convenient because of the position of the cylinders and the relation of the instrument board thereto. We have not shown the lock mechanism, as any 40 suitable lock may be used so long as it is provided with a bolt adapted to engage against a series of shoulders 30, 31 and 32 formed near the end of the bar 12. When 45 the bar 12 is pushed into its innermost position, thus locking the cover to the casing, and short circuiting the spark plugs, the bolt 33 of the lock engages against the shoulder 32. When it is desired to operate the vehicle the lock is released and the 50 spring 13 retracts the bar until the bolt 33 of the lock engages the shoulder 31. In this position the springs 25 are out of contact with the spark plugs and the engine may be operated, but the cover is still effectively 55 locked on the casing. If the cover is to be removed the lock is again operated to withdraw the bolt 33 out of the path of the bar 12 proper, but into such a position that the shoulder 30 engages against the bolt and 60 prevents the bar from being entirely drawn out from the guide 18. The cover may then be removed by tilting it in a counter-clockwise direction about the lugs 15 until the flange on the cover is clear of the upper edge 65 of the casing when it may be removed bodily

and access may be had to the interior of the casing for the purpose of cleaning or replacing the spark plugs or wires.

Any convenient type of lock mechanism may be employed, either a key-operating 70 lock or a combination lock, and it is unnecessary to describe the lock mechanism in detail. It may of course be so constructed that when a user enters a car and unlocks the lock the bar or plunger 12 may then be 75 operated to close the circuit through the spark plugs whether the key, in case a key lock is used, remains in the lock or not, and also the lock may be automatic so that the movement of the plunger into its operative 80 position holds it there until the lock is again operated by the user.

The present invention when installed on a 85 car is inconspicuous as everything except the lock and end of the bar are concealed under the hood, and it constitutes an effective lock for the ignition system of the automobile. The casing may be broken into to permit the removal of the springs 25 from 90 their position against the spark plugs, but any method which may be adapted to break open the box will also either injure or destroy the spark plugs, and hence render the motor temporarily inoperable. The casing may be made of hardened pressed steel so 95 that it will resist any ordinary methods that may be used to break into it, or it may be made of thick cast material which will be practically equally difficult to break into.

100 Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:—

1. The combination with an internal combustion engine having a plurality of aligned cylinders each provided with a spark plug therein, an open casing mounted on said cylinders about said spark plugs, a cover for said casing, and a bar slidably mounted in said casing, said bar being slidable into a position electrically disconnecting said spark plugs, and said bar being also adapted to lock said cover on said casing by said slid- 110 able disconnecting movement.

115 2. The combination with an internal combustion engine having a plurality of aligned cylinders each provided with a spark plug therein, an open casing mounted on said cylinders about said spark plugs, a cover for said casing, a bar slidably mounted in said casing, and extending exteriorly therefrom, said bar being slidable into a position electrically disconnecting said spark plugs, and said bar being also adapted to lock said 120 cover on said casing and lock means oper- 125 130

able exteriorly of said casing, said means co-operating with stepped shoulders on said bar to lock said bar in each of several positions.

5 3. The combination with an internal combustion engine having a plurality of aligned cylinders each provided with a spark plug therein, an open casing mounted on said cylinders about said spark plugs, a cover for said casing, a bar slidably mounted in said casing and extending exteriorly therefrom, said bar being slideable into a position electrically disconnecting said spark plugs and

said bar being also adapted to lock said cover on said casing by said disconnecting movement, resilient means normally tending to retain said bar out of contact with said spark plugs, and lock means operable exteriorly of said casing, said means co-operating with means on said bar to lock said bar in each of several positions.

Signed by us, this 9th day of September, 1921.

JAMES L. MYERS.
WALTER J. SIX.
